Des. 206,800

Patented Jan. 31, 1967

206,800

ELECTRICAL CONNECTOR PLUG COMPONENT

Elliott Goldbaum, Brooklyn, and Gordon L. Ablett, New York, N.Y., assignors to Lehigh Valley Industries, Inc., New York, N.Y., a corporation of Delaware

Original design applications May 25, 1964, Ser. No. 80,127 and Ser. No. 80,139. Divided and this application Nov. 1, 1965, Ser. No. 87,960

Term of patent 14 years

(Cl. D26—1)

FIG. 1.

FIG. 2.

FIG. 3.

FIG. 4.

FIG. 5.

FIG. 6.

FIG. 7.

FIG. 9.

FIG. 8.

FIG. 10.

FIG. 11.

FIG. 12.

FIG. 1 is a side elevational view of an electrical connector plug component, showing one form of our new design wherein a six wire system is utilized;

FIG. 2 is an opposite side elevational view of the form shown in FIG. 1;

FIG. 3 is a front end elevational view of the form shown in FIG. 1;

FIG. 4 is a bottom plan view of the form shown in FIG. 1;

FIG. 5 is a top plan view of the form shown in FIG. 1;

FIG. 6 is a rear end elevational view of the form shown in FIG. 1;

FIG. 7 is a side elevational view of an electrical connector plug component showing another form of our new design wherein a seven wire system is utilized;

FIG. 8 is a front end elevational view of the form shown in FIG. 7;

FIG. 9 is an opposite side elevational view of the form shown in FIG. 7;

FIG. 10 is a rear end elevational view of the form shown in FIG. 7;

FIG. 11 is a top plan view of the form shown in FIG. 7; and

FIG. 12 is a bottom plan view of the form shown in FIG. 7.

This application is a division of each of applicants' prior copending applications, Serial Numbers D. 80,127 and D. 80,139, both filed May 25, 1964, and both abandoned subsequent to filing this application.

We claim:

The ornamental design for an electrical connector plug component, as shown and described.
